US0D1105389S

(12) United States Design Patent (10) Patent No.: US D1,105,389 S
(45) Date of Patent: * Dec. 9, 2025

(54) AROMATHERAPY DIFFUSER

(71) Applicant: Wenlian Chen, Ganzhou (CN)
(72) Inventor: Wenlian Chen, Ganzhou (CN)
() Term: 15 Years
(21) Appl. No.: 29/941,327
(22) Filed: May 9, 2024
(51) LOC (15) Cl. 28-03
(52) U.S. Cl. USPC D23/366
(58) Field of Classification Search
USPC D23/355-369

(57) CLAIM

The ornamental design for an aromatherapy diffuser, as shown and described.

DESCRIPTION

FIG. 1 is a front top right side perspective view for an aromatherapy diffuser, showing my new design;

FIG. 2 is a rear bottom left side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof;

FIG. 6 is a right side elevational view of FIG. 1 thereof;

FIG. 7 is a top plan view of FIG. 1 thereof; and,

FIG. 8 is a bottom plan view of FIG. 1 thereof.

The broken lines in the drawings illustrate portions of the aromatherapy diffuser that form no part of the claimed design.

1 Claim, 8 Drawing Sheets
